[57] CLAIM

The ornamental design for an automobile tire, as shown and described.

DESCRIPTION

FIG. 1 is a perspective view of the automobile tire, showing the new design;

FIG. 2 is a front view of the automobile tire, the top plan view and the bottom plan view appearing the same as the front view;

FIG. 3 is a rear view of the automobile tire;

FIG. 4 is a right-side view of the automobile tire;

FIG. 5 is a left-side view of the automobile tire;

FIG. 6 is an enlarged fragmentary front view, showing the portion of X—X' in FIG. 3; and,

FIG. 7 is a sectional view, taken on line 7—7 of FIG. 6.

FIG. 1

FIG. 2

FIG. 3

FIG. 4

FIG. 5

FIG. 6

FIG. 7
